(57) **CLAIM**

The ornamental design for a charging box for earphones, as shown and described.

DESCRIPTION

FIG. 1 is a front, top, right perspective view of a charging box for earphones, showing our new design closed in a first configuration.

FIG. 2 is a front, bottom, left perspective view thereof.

FIG. 3 is a front view thereof.

FIG. 4 is a back view thereof.

FIG. 5 is a left view thereof.

FIG. 6 is a right view thereof.

FIG. 7 is a top view thereof.

FIG. 8 is a bottom view thereof.

FIG. 9 is a front cross sectional view thereof, taken in the direction of line 9-9 of FIG. 7.

FIG. 10 is a front, top, right perspective view of the charging box for earphones of FIG. 1, shown open in a second configuration.

FIG. 11 is a front, bottom, left perspective view thereof.

FIG. 12 is a front view thereof.

FIG. 13 is a back view thereof.

FIG. 14 is a left view thereof.

FIG. 15 is a right view thereof.

FIG. 16 is a top view thereof.

FIG. 17 is a bottom view thereof; and,

FIG. 18 is a front, top, right perspective view of the charging box for earphones of FIG. 1, shown open in a second configuration, and in a condition of use for clarity of disclosure.

The broken lines in the figures show portions of the charging box for earphones that form no part of the claimed design.

1 Claim, 18 Drawing Sheets
